(57) **CLAIM**

The ornamental design for an aerosolizer, as shown and described.

DESCRIPTION

FIG. 1 is a top perspective view of an aerosolizer showing our new design.

FIG. 2 is a bottom perspective view thereof.

FIG. 3 is a side view thereof, the aerosolizer being rotationally symmetric such that all side views are the same as one another.

FIG. 4 is a top plan view thereof; and,

FIG. 5 is a bottom plan view thereof.

The broken lines in the figures represent features of the article of manufacture that form no part of the claimed design.
